US00D888289S

(12) **United States Design Patent** (10) Patent No.: **US D888,289 S**
(45) Date of Patent: **** Jun. 23, 2020**

- (54) **SLAB COMPRISING PARTICULATE MINERAL MIXTURE**
- (71) Applicant: **Cambria Company LLC**, Eden Prairie, MN (US)
- (72) Inventors: **Jon Louis Grzeskowiak, II**, Prior Lake, MN (US); **Summer Lane Kath**, Eden Prairie, MN (US); **Martin E. Davis**, Excelsior, MN (US)
- (73) Assignee: **Cambria Company LLC**, Eden Prairie, MN (US)
- (**) Term: **15 Years**
- (21) Appl. No.: **29/668,593**
- (22) Filed: **Oct. 31, 2018**
- (51) LOC (12) Cl. **25-01**
- (52) U.S. Cl. **D25/149; D5/44**
- (58) **Field of Classification Search**
USPC D25/138, 149, 151; D5/5, 8, 43, 44
CPC B44F 9/04; B32B 9/00; B44D 5/00
See application file for complete search history.

(57) **CLAIM**

The ornamental design for a slab comprising particulate mineral mixture, as shown and described.

DESCRIPTION

The file of this patent contains at least one drawing/photograph executed in color. Copies of this patent with color drawing(s)/photograph(s) will be provided by the Office upon request.

The sole FIGURE is a top plan view of a slab comprising particulate mineral mixture, showing our new design. The depicted surface of the slab comprising particulate mineral mixture is flat.

**1 Claim, 1 Drawing Sheet
(1 of 1 Drawing Sheet(s) Filed in Color)**
